UNITED STATES PATENT OFFICE.

FERDINAND IMHORST, OF NEW YORK, N. Y.

IMPROVEMENT IN WASH-BASINS.

Specification forming part of Letters Patent No. 134,285, dated December 24, 1872.

To all whom it may concern:

Be it known that I, FERDINAND IMHORST, of the city, county, and State of New York, have invented a new and useful Improvement in Wash-Basins; and I do hereby declare the following to be a full, clear, and exact description thereof, which will enable those skilled in the art to make and use the same, reference being had to the accompanying drawing forming part of this specification, in which drawing—

Figure 1 represents a longitudinal vertical section of my invention, and Fig. 2 is a plan or top view of the same when the cover is removed.

Similar letters indicate corresponding parts. This invention consists in a wash-basin which is made in an oblong form and provided with a raised seat, formed by a flange which projects over the edges of the basin on the inside and outside, said raised seat being intended to enable a person to rest his body conveniently while washing the legs and the lower portions of the body, and the object of the flange being to produce a broad surface for the seat, and to prevent the water from being spilled. On the side of my basin is a pocket for soap, and the top or cover is hollow, forming a receptacle for brushes, pumps, and other utensils employed in the operation of washing.

In the drawing, the letter A designates a wash-basin, which is made in an oblong form, as shown in Fig. 2. The rim B of one-half of my basin is raised above the other half, and

it forms a support for the body during the operation of washing. Said raised rim is provided with a flange, a, projecting over the inside to prevent the contents of the basin from being splashed out during the operation of washing, and said flange also projects over the outside of the rim so as to increase its width and to produce a convenient seat. On the side of the basin A, either inside or outside, is applied a pocket, C, for soap, and in the top of my basin is fitted a cover, D, which is hollow, forming a receptacle, E, for brushes, pumps, and other articles used in washing the lower portions of the body.

My basin can be constructed of sheet metal, or of any other suitable material, and, on account of its oval or oblong shape, it affords plenty space for the operation of washing, and, at the same time, it does not occupy any superfluous room.

What I claim as new, and desire to secure by Letters Patent, is—

1. A wash-basin made in oblong form and having at one end a flanged raised rim or seat, B, substantially as and for the purpose specified.
2. The cover D of an oval or oblong wash-basin, formed with the receptacle E, substantially as herein shown, and for the purpose set forth.

FERDINAND IMHORST.
